CLAIM

The ornamental design for a fishing gear retrieval apparatus, as shown and described.

DESCRIPTION

FIG. 1 is a front elevation view of a first embodiment of a fishing gear retrieval apparatus showing my new design.

FIG. 2 is rear elevation view of the first embodiment of the invention

FIG. 3 is top plan view of the first embodiment of the invention.

FIG. 4 is a bottom plan view of the first embodiment of the invention.

FIG. 5 is an environmental view of the first embodiment of the invention showing the invention installed in a rope.

FIG. 6 is a front elevation view of a second embodiment of the fishing gear retrieval apparatus.

FIG. 7 is rear elevation view of the second embodiment of the invention

FIG. 8 is top plan view of the second embodiment of the invention.

FIG. 9 is a bottom plan view of the second embodiment of the invention; and,

FIG. 10 is an environmental view of the second embodiment of the invention showing the invention installed in a rope.

The dashed lines showing the rope and dips in FIGS. 5 and 10 are for illustrative purposes only and form no part of the claimed design.
